INVENTOR.

BY James M. Wardlow,

Victor J. Evans

ATTORNEY.

UNITED STATES PATENT OFFICE.

JAMES MORGAN WARDLOW, OF ADA, OKLAHOMA.

TOOL.

Application filed July 7, 1919. Serial No. 309,063.

To all whom it may concern:

Be it known that I, JAMES M. WARDLOW, a citizen of the United States, residing at Ada, in the county of Pontotoc, and State of Oklahoma, have invented new and useful Improvements in Tools, of which the following is a specification.

This invention relates to garden tools and has particular application to the connection 10 between the blade and handle therefor, whereby anyone of a number of different type blades can be easily and quickly associated with or detached from the handle when desired.

15 The nature and advantages of the invention will be better understood when the following detail description is taken in connection with the accompanying drawings, the invention residing in the construction, combination and arrangement of parts as claimed.

In the drawing forming part of this specification like numerals of reference indicate similar parts in the several views wherein:—

20 Figure 1 is a view of a hoe constructed in accordance with my invention.

Figure 2 is a vertical sectional view taken on the line through the blade and the connecting means therefor.

30 Figure 3 is a detail sectional view taken on line 3—3 of Figure 2.

Figure 4 is a fragmentary front view.

Figure 5 is a fragmentary sectional view.

35 Figure 6 shows several types of blades designed for use in connection with the invention.

Referring to the drawing in detail, 10 indicates a hoe blade of well known construction, 11 a handle therefor, and 12 the socket connection between the handle and blade, respectively. Upon reference to Figure 3 it will be noted that this socket connection is formed to provide an elongated substantially flat end portion 13 adapted to be arranged 40 against one side of the blade 10. The lower edge of this flat end portion is provided with a notch 14 which is adapted to receive the offset extremity 15 of an adjusting screw 17 which is adjustable transversely through the 45 socket member at a point immediately at the rear of the flat end portion 13. The upper end of the screw is provided with a winged nut 18, while the offset extremity of this screw is provided with a head 19. The opposite end or edge of the frame portion 13 is bent forwardly and downwardly to pro-

vide a flange 20 which is also connected to the portion 13 by means of short pins 21. The blade 10 at a point in its surface is provided with a key hole slot 22 which receives the offset headed extremity of the adjusting bolt, while the upper edge of the blade is provided with notches 24 which receive the pins 21 when this edge of the blade is positioned between the flat portion 13 and the flange 20 thereof. If desired, a small plate 25 may be secured to one side of the blade to reinforce the latter at its point of connection with the pins 21, in which instance the plate 25 is also provided with notches 26 which coincide or align with the notches 24 of the blade. To associate the parts, the thumb nut is turned in the proper direction to permit the headed extremity of the adjusting screw to assume a position below the adjacent edge of the flat portion 13 of the socket. The head of the adjusting screw is then inserted through the enlarged portion of the key hole slot of the blade, during which time the upper edge of the 50 blade is positioned within a recess formed by the flange 20 with the notches thereof arranged to receive the pins 21. Manifestly, as the thumb nut is tightened, the offset extremity of the adjusting screw is lifted into 55 the small or reduced portion of the key hole slot, moving the blade slightly so that the notches thereof will receive the pins 21. The pins manifestly prevent turning of the blade relative to the socket connection. The parts 60 can be just as easily disassembled by loosening the thumb nut sufficient to permit the headed extremity of the adjusting screw to be removed from the key hole slot of the blade.

95 In Figure 6 I have shown a number of different type blades, certain of which are provided with tines and all of which except the rake have duplex working extremities. Aside from this fact, the blades A and B in 100 Figure 6 are constructed and attached to the handle in the same manner as described in connection with the blade 10. In each of these instances, the blade is provided with a key hole slot 30 and spaced notches 31 at one 105 edge of the body portion thereof. They are also provided with reinforcing plates 32 having notches 33 aligned with the notches 31.

The rake indicated at C in Figure 6 is provided with a key hole opening or slot 110 35 between its intermediate tines 36, while the upper edge of the rake is also provided

with the spaced notches 37 and a reinforcing plate 38 having the notches 39 alined with the notches 37. The rake is associated with the handle in the same manner as that 5 disclosed and described in connection with the blade 10. The blade indicated at D in Figure 6 varies from the other blades in that it is provided with a transverse slot 40 at an appropriate point in its length 10 and that one edge of the slot is formed with the spaced notches for the reception of the pins 21. The reinforcing plate 42 is secured to one side of the blade as the notches 43 in alignment with the notches 41. 15 The blade is otherwise constructed the same as the other blades so far as the invention is concerned, having a key hole slot 44 for the reception of the offset extremity of the adjusting bolt 17 and adapted to be secured 20 to the handle in the same manner as the blade 10.

While I have shown and described what I consider the preferred embodiment of the invention I desire to have it understood 25 that I do not limit myself in this connection, inasmuch as such changes may be resorted to when desired as fall within the scope of what is claimed.

Having thus described my invention 30 what I claim is:—

A tool of the class described comprising,

a blade, a handle provided therefor having a socket connection with the handle and blade, the socket connection being formed to provide an elongated substantially flat 35 end portion adapted to be arranged against one side of the blade, an adjusting screw adjustable transversely through the socket member at a point immediately at the rear of the flat end portion, said adjusting screw 40 having an off set extremity provided thereon, the lower edge of said flat end portion having a notch formed therein to receive the off set extremity of said screw, a winged nut provided on the upper end of the screw 45 and a head provided on the off set extremity of the latter, the opposite end of the flat portion being bent forwardly and backwardly to provide a flange which is connected to the flat end portion, the blade 50 having a key hole slot formed therein to receive the off set headed extremity of the adjusting screw, and the upper edge of said blade having notches formed therein to receive pins for connecting said flange to the 55 end portion, a reinforcing plate secured to one side of said blade and having notches therein which coincide with the notches of the blade.

In testimony whereof I affix my signature. 60

JAMES MORGAN WARDLOW.
